[57] CLAIM

The ornamental design for a floor drain finished extension apparatus, as shown.

DESCRIPTION

FIG. 1 is a top perspective view of the floor drain finished extension apparatus of the present invention;
FIG. 2 is a rear plan view of the floor drain finished extension apparatus of FIG. 1;
FIG. 3 is a left side plan view of the floor drain finished extension apparatus of FIG. 1;
FIG. 4 is a right side plan view of the floor drain finished extension apparatus of FIG. 1;
FIG. 5 is a top plan view of the floor drain finished extension apparatus of FIG. 1; and,
FIG. 6 is a bottom plan view of the floor drain finished extension apparatus of FIG. 1.
